UNITED STATES PATENT OFFICE

2,222,349

COMPLETE COMPACT ADJUSTABLE BOILER
SUPERHEATER

William Anthony Jones, Port Richmond, N. Y.

Application October 15, 1938, Serial No. 235,150

7 Claims. (Cl. 122—451.1)

My invention is a development of the Adjustable boiler superheater, for which United States Patent No. 1,929,532 was granted to me Oct. 10, 1933, which dominates this application.

5 This development is for a complete unit including, a furnace in which fuel is burned and whose surfaces are lined with vertical helical coils of tube supplied with water at their lower ends, through a float valve above, and which discharge 10 superheated steam through an adjustable automatic thermostatic valve at their upper ends which valve adds a resistance of flow depressing the water within the tubes enough to give sufficient surface of tubes filled with steam to give 15 the required superheat to the steam from radiation, an intermediate gas pass, similar to the furnace pass but, in which gases flow upward and in which the water within the tubes is depressed by a manually adjustable valve adding a resistance 20 of flow of steam to mingle with the steam from the tubes of the furnace pass, and a convection pass in which gases flow downward and which is filled with vertical helical coils of tubes which are supplied with water at their lower ends and 25 discharge superheated steam through an adjustable automatic thermostatic valve at their upper ends which adds a resistance of flow depressing the water within the tubes enough to give sufficient surface of tubes filled with steam to give 30 the required superheat.

The water supplied to the lower ends of all helical coils has a pressure due to its height below the float valve, and the pressure equivalent of its downward velocity, in addition to the steam 35 outlet pressure.

The float valve is shown with the float supported by a spring and by a water pressure cylinder below, which is supplied with water of feed pressure through a central tube.

40 A manually operated pilot valve controls the flow of feed water from this pressure cylinder to the boiler so that when the manually operated pilot valve is opened, wide, the float valve opens and floods all helical tubes, the upper headers and 45 the drum or final header, washing them out through the blow off valve.

When the pilot valve is closed tight, the pressure in the cylinder rises and closes the float valve. A slight opening of the pilot valve reduces the pressure in the cylinder so that the float valve maintains the desired level of feed water above the bottom of the helical coils.

Evidently a separate valve could be used for flooding.

55 The surface to give the required superheat

from radiant heat will be different from the surface required to give the same superheat from convection and the separate adjustable automatic thermostatic valves maintain the required temperature of steam in each case, after each 5 valve is adjusted.

In order that the gases resulting from combustion may be cooled to nearly the temperature of the feed, it is desirable that the gases pass downward through the economizer section receiving heat by convection.

When gases pass upward in the furnace, they may pass downward in the economizer section without an intermediate pass.

When gases pass downward in the furnace, an 15 intermediate upward pass may conduct the gases upward so that they can pass downward in the economizer section, with less total height than would result from the economizer section being 20 below the furnace.

Where an intermediate pass is used, a separate 25 adjustable valve may control the flow of steam from the intermediate pass to mingle with the steam from the furnace beyond which it will pass through the adjustable automatic thermostatic valve which controls the temperature of the 30 superheated steam from the furnace surface.

In general the extent of the surface to give the 35 desired superheat from radiant heat will be less than the surface required to give the same superheat by convection from the cooler gases beyond the furnace, and therefore this valve for the steam from the intermediate pass will be required to depress the water level in the helical elements in the intermediate pass below the water 40 level in the helical elements which line the furnace.

An arrangement with an intermediate pass is 45 illustrated in the drawings accompanying this application.

Referring to the accompanying drawings:

Figs. 1 and 2 are upper and lower parts of a side view with part of the height broken out to avoid too small a scale.

Fig. 3 is a part plan view, partly in section on 45 lines, 21—21 and 22—22, through the horizontal center of the drum or final header, partly in section on lines 41—41 and 42—42, through the access door in the front wall at the bottom of the furnace and through tubes directly below the 50 upper horizontal headers, partly in section on line, 6—6, showing tubes, of the furnace and of the intermediate pass, entering the lower horizontal headers, and partly in section on line, 7—7, showing tubes, of the intermediate pass and of 55

the convection pass, entering lower horizontal headers and with baffle plate between.

Figs. 4, 5, 6, and 7 are four parts of a sectional front view with spaces between to avoid too small a scale, on line 5—5.

Fig. 8 is a part sectional plan view showing to a larger scale, a helical element made of six concentric coiled tubes and the enclosing casing having inner and outer metal plates with insulation between. Fig. 9 is a part sectional side view of this arrangement. Tubes may connect to horizontal headers in two or more lines.

Fig. 10 is a part sectional plan view showing, to a larger scale, helical elements each made of four coils with centers of alternate coils offset, and with the enclosing metal casing and insulation.

Fig. 11 is a part plan view of an adjustable float valve for controlling the feed supply.

Fig. 12 is an enlarged part sectional elevation 20 of the float valve for controlling the feed supply.

Like reference characters indicate like parts in the several views.

In the complete compact adjustable boiler superheater, which I have chosen for purposes of 25 illustration, feed pipe, 1, supplies liquid to float valve, 2, maintaining level, 3, of liquid in container, 4, having a horizontal part, 5, supplying liquid to headers, 6, 6a, 6b, and 6c, 6d, 6e, 6f, which supply liquid to the lower ends of vertical 30 helical coils 9, 9a, 9b, 9c, 9d, 9e, 9f, and 9g.

Upper ends of coils 9, 9a, and 9b in the furnace are connected to upper headers 11, 11a, and 11b, which discharge into space, 14, of drum or final header, 12, and thence through thermostatic valve, 13, to space, 15 and outlet nozzle, 37.

Screwed plugs, p6, and p11, close headers at ends away from drum or final header.

Plates, 23, 23a, and 23b, attached to drum or 40 final header, 12, prevent the flow of steam from space, 14, 14a, and 14b, to space, 15, except through valves, 13, 13a, and 13b. These valves as shown cannot be completely closed.

Thermostatic valve, 13, is represented as a 45 plate, 17, with hub sliding on sleeve, 18, which has a hub, 19, at its inner end limiting the position to which plate, 17, can be moved towards the plate, 23, by a spring, 20, between plate, 17, and a distance sleeve, 21, extending to the drum or 50 final header, end plug, 26.

Outer end of sleeve, 18, is adjustably located by hand wheel, 31, with differential screw.

Feed pipe, 1, inside of sleeve, 18, and distance sleeve, 21, insure that sleeve, 18, will be cooler 55 than the drum or final header and will not expand endways as much from the heat of the steam. An outer sleeve, 24, further insulates sleeve, 18, from the heat of the steam.

Holes, 25, in plate, 23, are not opposite to 60 similar holes in plate, 17, and the area for steam flow is controlled by the distance between the plates and thus permits more flow of steam to space, 15, as the distance between plates, 17 and 23, increases with the expansion of the drum or 65 final header and differential screw enables this space to be very finely adjusted.

Thermometers, 57, 57a, 57b, and 57c, indicate the temperature of the steam and will guide the 70 operator in adjusting the valves, 13, 13a, and 13b.

The thermostatic valve, 13b, for depressing the water level, 16b, in the economizer section is just as described for valve, 13, with separate 75 differential adjusting screw hand wheel, 31b, for

depressing the water level, 16b, to give the same superheat from the cooler gases in this pass. Figures in this case are followed by the letter, b.

Upper ends of coils, 9b, 9a, 9c, of the intermediate pass are connected to headers, 11c, and 11d, which discharge into space, 14a, and thence through adjustable valve, 13a, whose function it is to maintain such a pressure in space, 14a, over the pressure in space, 14, as will cause the level, 16a, of the liquid in these helical coils, 9b, 9a, 9c, 10 of the intermediate pass to be sufficiently below the level, 16, to compensate for the cooler gases in the intermediate pass as compared with the furnace.

Thermometers, 57 and 57a, will show when 15 valve, 13a, is properly adjusted to give the required temperature of steam in space, 14a, without the necessity of this valve being thermostatic, which would be less simple.

Nozzles, 36 and 36b, connect to safety valves 20 above the pressure spaces, 14 and 14b.

Screwed plugs, 26 and 26b, with soft packing, 27 and 27b, are represented as closing the ends of the steam drum or final header, 12.

Glands, 28 and 28b, with packing, 29 and 29b, 25 are represented where sleeves, 21 and 21b, pass through drum or final header end plugs, 26 and 26b.

Packings, 1a and 1b, prevent leakage at feed 30 pipe, 1.

A gland, 28a, and packing, 29a, prevent steam leakage where valve stem, 19a, passes through the side of the drum or final header.

Valve hand wheel, 31a, with screw moves plate, 17a, nearer to or further from plate, 23a, to form 35 the valve, 13a, from the intermediate pass. Holes extend beyond plate, 17a, so that this valve, 13a, can not be completely closed.

Tube, 30, drains drum or final header, 12, to 40 container, 4, of float valve, 2.

Drain and blowoff valve, 55, permits all liquid to be drained away.

Fig. 12, shows a spring, 100, for supporting the weight of the float valve, 2, and a cylinder, 101, slightly more than balancing the feed pressure 45 on the top of the valve, by feed pressure passing down through pipe, 102, and through holes, 103.

Holes, 106, discharge liquid downward, from 50 valve, 104, so that this liquid will induce a downward flow of liquid in pipe, 4, superimposed over the downward flow caused by the weight of the liquid.

A valve, 104, operated by hand wheel, 105, and 55 screwed valve stem, controls flow of feed water from cylinder, 101, so that when valve, 104, is opened float valve, 2, opens and floods all helical coils and spaces in the steam drum or final header, washing them out through drain valve, 55.

In Fig. 9, elements each made of six concentric helixes, 9g, illustrate the possibility of close coiled tubes for protecting furnace casing and with greater capacity for very hot furnace fire. As 60 compared with a four tube close coiled helix, 65 the capacity is about one and a half due to increase flow area and the square root of one and a half, due to increased height of pitch, giving about 1.83 times the limiting capacity.

As shown, columns, 38 and 39, support ends 70 of steam drum or final header, 12, and ends of upper transverse beams, 40 and 41, and ends of lower transverse beams, 42 and 43.

Columns, 64 and 65, support other ends of 75 beams, 40, 41, 42, and 43.

Longitudinal beams, 44 and 45, support upper headers, 11, 11a, 11b, 11c, 11d and 11e.

Longitudinal beams, 46 and 47, support lower headers, 6, 6a, 6b, 6c, 6d, 6e and 6f.

5 Fuel burner, 48, is represented at the top of the furnace and door, 49, in the wall at the bottom of the furnace.

Spent gas outlet, 50, is shown at the lower part of the economizer section.

10 Evidently the thermostatic valve may be operated by the difference in expansion of bronze and of steel members heated by the steam or by the difference in expansion of any two members due to difference of temperature or of difference 15 of material or of both.

15 As stated above, the intermediate pass may be omitted, and the apparatus described may be otherwise varied without departing from my invention.

20 Evidently the coils may discharge steam directly into the drum or final header without intermediate headers and the final header need not be large enough for a man to enter it if the inner parts are designed to be assembled outside 25 and inserted from the end or ends of the final header.

I claim:

1. In combination, in a complete compact adjustable boiler superheater, for heating a liquid 30 to its boiling temperature, evaporating the liquid into vapor and superheating the vapor to the desired temperature above the boiling temperature, means providing a passage for gases flowing in series through, a furnace chamber lined with 35 vertical helixes of multiple tubes, forming one group of tubes, an intermediate chamber lined with vertical tubular helixes, alternately right hand and left hand and with offset centers, forming another group of tubes, and a convection chamber through which gases flow downward and which is filled with vertical tubular helixes, alternately right hand and left hand and with offset centers and having more length of tube per foot of height in the lower part than 40 in the upper part, forming another group of tubes, all helixes being supplied with liquid of constant head to their lower ends, and being connected to a header at their upper ends, and with the upper end of each group discharging 45 vapor into a separate vapor space in the header for that group and thence, either directly through an adjustable thermostatic valve, or through a manually operated valve into a space in the header in which the pressure is maintained by such an adjustable thermostatic valve, responsive to the temperature of the vapor discharged into said space, thus depressing the liquid within each group of tubular helixes enough to give sufficient vapor filled surface to 50 give the required outlet temperature of vapor above the boiling temperature.

2. In combination, in a complete compact adjustable boiler superheater, for heating a liquid

55 to its boiling temperature, evaporating the liquid into vapor and superheating the vapor to the desired temperature above the boiling temperature, means providing a passage for gases flowing in series through, a furnace chamber lined with vertical helixes of multiple tubes, forming one group of tubes, and a convection chamber through which gases flow downward and which is filled with vertical tubular helixes, alternately right hand and left hand and with offset centers and having more length of tube per foot of height in the lower part than 60 in the upper part, forming another group of tubes, all helixes being supplied with liquid of constant head to their lower ends, and being connected to a header at their upper ends, and with the upper end of each group discharging vapor into a separate vapor space in the header for that group and thence, either directly through an adjustable thermostatic valve, or through a manually operated valve into a space in the header in which the pressure is maintained by such an adjustable thermostatic valve, responsive to the temperature of the vapor discharged into said space, thus depressing the liquid within each group of tubular helixes enough to give sufficient vapor filled surface to 65 give the required outlet temperature of vapor above the boiling temperature.

70 3. In combination, in a complete compact adjustable boiler superheater, for heating a liquid

75 to its boiling temperature, evaporating the liquid into vapor and superheating the vapor to the desired temperature above the boiling temperature, means providing a passage for gases flowing in series through, a furnace chamber lined with vertical helixes of multiple tubes, forming one group of tubes, and a convection chamber through which gases flow downward and which is filled with vertical tubular helixes, alternately right hand and left hand and with offset centers and having more length of tube per foot of height in the lower part than in the upper part, forming another group of tubes, all helixes being supplied with liquid of constant head to their lower ends, and being connected to a header at their upper ends, and with the upper end of each group discharging vapor into a separate vapor space in the header for that group and thence, either directly through an adjustable thermostatic valve, or through a manually operated valve into a space in the header in which the pressure is maintained by such an adjustable thermostatic valve, responsive to the temperature of the vapor discharged into said space, thus depressing the liquid within each group of tubular helixes enough to give sufficient vapor filled surface to give the required outlet temperature of vapor above the boiling temperature.

75 4. In combination, in a complete compact ad-

height in the lower part than in the upper part, forming another group of tubes, all helixes being supplied with liquid of constant head to their lower ends, and being connected to a header at their upper ends, and with the upper end of each group discharging vapor into a separate vapor space in the header for that group and thence, either directly through an adjustable thermostatic valve, or through a manually operated valve into a space in the header in which the pressure is maintained by such an adjustable thermostatic valve, responsive to the temperature of the vapor discharged into said space, thus depressing the liquid within each group of tubular helixes enough to give sufficient vapor filled surface to give the required outlet temperature of vapor above the boiling temperature.

3. In combination, in a complete compact adjustable boiler superheater, for heating a liquid 20 to its boiling temperature, evaporating the liquid into vapor and superheating the vapor to the desired temperature above the boiling temperature, means providing a passage for gases flowing in series through, a furnace chamber lined with 25 vertical helixes of multiple tubes, forming one group of tubes, and a convection chamber through which gases flow downward and which is filled with tubular helixes, having more length of tube per foot of height in the lower part than 30 in the upper part, forming another group of tubes, all helixes being supplied with liquid of constant head at their lower ends, and being connected to a header at their upper ends, and with the upper end of each group discharging 35 vapor into a separate vapor space in the header for that group and thence, either directly through an adjustable thermostatic valve, or through a manually operated valve into a space in the header in which the pressure is maintained by such an adjustable thermostatic valve 40 responsive to the temperature of the vapor discharged into said space, thus depressing the liquid within each group of tubular helixes enough to give sufficient vapor filled surface to 45 give the required outlet temperature of vapor above the boiling temperature.

4. In combination, in a complete compact adjustable boiler superheater, for heating a liquid 50 to its boiling temperature, evaporating the liquid into vapor and superheating the vapor to the desired temperature above the boiling temperature, means providing a passage for gases flowing in series through, a furnace chamber lined with vertical helixes of multiple tubes, forming one group of tubes, and a convection chamber through which gases flow downward and which is filled with tubular helixes, forming another group of tubes, all helixes being supplied with liquid of constant head at their lower ends, and being connected to a header at their upper ends, and with the upper end of each group discharging 55 vapor into a separate vapor space in the header for that group and thence, either directly through an adjustable thermostatic valve, or through a manually operated valve into a space in the header in which the pressure is maintained by such an adjustable thermostatic valve, responsive to the temperature of the vapor discharged into said space, thus depressing the liquid within each group of tubular helixes enough to give sufficient vapor filled surface to 60 give the required outlet temperature of vapor above the boiling temperature.

5. In combination, in a complete compact adjustable boiler superheater, for heating a liquid 65 to its boiling temperature, evaporating the liquid into vapor and superheating the vapor to the desired temperature above the boiling temperature, means providing a passage for gases flowing in series through, a furnace chamber lined with vertical helixes of multiple tubes, forming one group of tubes, and a convection chamber through which gases flow downward and which is filled with vertical tubular helixes, alternately right hand and left hand and with offset centers and having more length of tube per foot of height in the lower part than 70 in the upper part, forming another group of tubes, all helixes being supplied with liquid of constant head to their lower ends, and being connected to a header at their upper ends, and with the upper end of each group discharging vapor into a separate vapor space in the header for that group and thence, either directly through an adjustable thermostatic valve, or through a manually operated valve into a space in the header in which the pressure is maintained by such an adjustable thermostatic valve, responsive to the temperature of the vapor discharged into said space, thus depressing the liquid within each group of tubular helixes enough to give sufficient vapor filled surface to 75 give the required outlet temperature of vapor above the boiling temperature.

5. In combination, in a complete compact ad-

justable boiler superheater, for heating a liquid to its boiling temperature, evaporating the liquid into vapor and superheating the vapor to the desired temperature above the boiling temperature, a chamber containing hot gases and vertical helixes of tubes, forming one group of tubes, discharging vapor into a space in a header in which the temperature is maintained by an adjustable thermostatic valve, responsive to the 10 temperature of vapor in such space, one or more other chambers containing cooler gases and vertical tubular helixes, forming one or more other groups of tubes, discharging vapor into a separate space, in the header, from each chamber, 15 the vapor discharging from one group passing through a manually operated valve into the space where the temperature is maintained by the thermostatic valve, thermometers indicating the temperature of vapor in each space.

20 6. In combination, in a complete compact adjustable boiler superheater, for heating a liquid to its boiling temperature, evaporating the liquid into vapor and superheating the vapor to the desired temperature above the boiling temperature, means providing a passage for gases flowing 25 in series through, a furnace chamber lined with vertical helixes of multiple tubes, forming one group of tubes, and a convection chamber through which the gases flow downward and 30 which is filled with vertical tubular helixes, forming another group of tubes, all helixes being

supplied with liquid of suitable head to their lower ends, and connected to a header at their upper ends, and with the upper ends of each group discharging vapor into a separate vapor space for that group, in the header, and with 5 means for separately controlling the flow of vapor through each group of tubes to maintain the desired outlet temperature.

7. In combination, in a complete compact adjustable boiler superheater, for heating a liquid 10 to its boiling temperature, evaporating the liquid into vapor and superheating the vapor to the desired temperature above the boiling temperature, means providing a passage for gases flowing 15 in series through, a furnace chamber lined with vertical helixes of multiple tubes, forming one group of tubes, receiving liquid from lower headers and discharging vapor through upper headers into a separate space in a drum, and a convection chamber through which gases flow 20 downward and which is filled with vertical tubular helixes, forming another group of tubes, receiving liquid from lower headers and discharging vapor through upper headers into a separate space in a drum, a manually operated valve 25 for causing a float valve to open to supply feed liquid to the lower ends of the helical coils, flooding all helical coils, the upper headers and the drum and washing them out through a blow off valve.

WILLIAM ANTHONY JONES.
